HOLD OPEN DEVICES FOR SINGLE ACTING SWINGING DOORS

Hans Frohlich, New York, N. Y., assignor to Bommer Spring Hinge Co., Inc., Landrum, S. C., a corporation of New York

Application September 24, 1956, Serial No. 611,454

2 Claims. (Cl. 16—55)

This invention relates to a hold open device for swinging doors, and more particularly to a device of this character combined with checking floor hinges for single acting swinging doors.

The principal object of the invention is to provide a mechanism which, when in operative position, maintains the swinging door open at about a right angle.

Another object of the invention is to provide a mechanism of the above character which embodies simple means for inactivating the hold open device.

A further object of the invention is to provide a hold open device for single acting swinging doors which includes means for controlling the forces required for closing the swinging door by varying the retaining force of the novel device.

A still further object of the invention is to provide a hold open device which is fully received in the housing of the floor hinge.

The invention resides essentially in the provision of a yieldably mounted roller which travels in an arc with the swinging door when the latter is opened or closed, and an adjustable retaining element or keeper suitably formed to engage the roller when the door is open at about right angle, and to thereby prevent the door from returning into its closed position. As the roller is yieldably mounted and urged against the keeper by a resilient element, a certain pressure exerted on the open swinging door causes the resilient element to yield and enables the roller to ride over the keeper, whereupon the swinging door is closed by the action of the floor hinge.

Various other features and attributes of the novel device will become apparent in the course of the following description of a preferred embodiment which is illustrated in the accompanying drawings, and the invention will be finally pointed out in the appended claims.

In the drawings,

Fig. 1 is a side elevational view of the checking floor type hinge which is partly broken away to reveal the hold open device in operative door-retaining position;

Fig. 2 is a top plan view of the structure shown in Fig. 1;

Fig. 3 is a section taken on line 3—3 in Fig. 1; and

Fig. 4 is another section taken on line 4—4 in Fig. 1.

Referring first to Figs. 1 and 2, the housing 10 of the door check rotatably supports the main spindle 11 to which is attached one end of the arm 12. The latter is also fastened to the swinging door (not shown) and rotates the spindle 11 when the door is being opened. The door closing mechanism (not shown) in the housing 10 normally urges the arm 12 into its dot-dash position 12' (see Fig. 2) to maintain the door closed. The spindle 11 is in the form of a double crank whose upper shaft 13 extends from the housing 10 to receive the arm 12, and whose lower shaft 14 is received in a suitable bearing in the screw plate 10a threaded into the bottom of casing 10. The connecting rod 15 of the closing mechanism in the housing 10 imparts rotational movement to

2

the crank and permanently urges the arm 12 to return from its position shown in full lines into the position 12' (see Fig. 2) when the door is closed. Such structure is known in the art, for example, in U. S. Patent No. 1,064,255, granted June 10, 1913, and does not form part of my invention.

The novel hold open device includes a plate 16 which is rigidly attached to the crank pin of spindle 11 by means of an integral connecting member 17, an L-shaped member 18 pivotally attached to the plate 16 by means of a pivot pin 19, a retaining roller 20 mounted on a shaft 21 between two flanges 22a, 22b (see Fig. 3) integral with the leg 18a of the L-shaped member 18, a short stem 24 anchored in the projecting spring support 23 integral with the plate 16, and a coil spring 25 which axially surrounds the stem 24 and bears against the leg 18a of the L-shaped member 18 to normally urge the roller 20 together with the leg 18a in the direction of arrow 26. The extent of such pivotal movement of the roller 20 is controlled by the other leg 18b of element 18 which abuts against the projection 23. A thumb screw 27 on the like in the free end of leg 18b permits adjustments of the extent of pivotal movement of leg 18a and of the roller 20 in the direction of arrow 26. A keeper 28 mounted on a shaft 29 rotatably supported in the top wall casing 10 has a projecting lip 30 which is in the path of the roller 20 when the swinging door is in the process of being opened. As shown in Fig. 1, which illustrates the hold open device in its operative door-retaining position, the roller 20 bears against the inner vertical surface 30a of the lip 30 which latter thus prevents the roller, together with the spindle 11 and arm 12, from returning into the original position when the door is closed. When sufficient pressure is exerted against the open swinging door in the direction of arrow 31 (see Fig. 2), the spring 25 yields and permits roller 20 to pivot with the member 18 to the extent that the roller can ride over the lip 30, whereupon the door is free to return to its closed position by the action of the hinge mechanism.

If it is desired to render the hold open device inactive, the lever 32 attached to the shaft 29 of the keeper 28 is moved into its dot-dash position 32' (see Fig. 2) which brings the lip 30 into the position 30' (see Fig. 3). The assembly on base plate 16 together with the spindle 11 is then free to rotate without impediment and the mechanism of the hinge immediately closes the swinging door.

The hold open device may also be inactivated by rotating the screw 27, whereby the leg 18a with roller 20 pivots around the pin 19 in a direction opposed to that of arrow 26 to compress the spring 25 and to move the roller away from the lip 30 of the keeper.

It may be observed in Fig. 4 that the lip 30 has a cam surface 30b which facilitates the passage of roller 20 thereover when the door moves from its closed toward its open position. By slightly varying the position of member 18 by means of screw 27, the force required for closing the door against the resistance of spring 25 may be controlled.

If the swinging door is pivoted somewhat beyond 90° and then suddenly released, the inertia of the moving door together with the closing force of the hinge mechanism in the housing 10 causes the leg 18a to compress the spring 25 and to enable roller 20 to ride over the lip 30 of the keeper.

The entire hold open device, with the exception of lever 32, is installed in the housing 10. When the position of element 18 is properly adjusted by means of screw 27, the hold open device requires no further attention.

What I claim and desire to protect by Letters Patent is:

1. In combination with a checking floor hinge for single acting swinging doors having a housing, a spindle project-

ing from said housing, and an arm attached to said spindle exteriorly of said housing, said arm being adapted to be connected with a swinging door; a hold open device including a base plate rigidly attached to said spindle and located within said housing, an L-shaped member, a pivot pin substantially at right angles to the axis of rotation of said spindle for supporting said L-shaped member on said plate, said L-shaped member having a first leg and a second leg both extending from said pivot pin, a roller attached to said first leg, a spring support on said base plate, said second leg having a free extremity adjacent said spring support, a resilient element between said spring support and said first leg for urging said roller in a direction causing said second leg to bear against said spring support, a shaft rotatably supported in said housing, a retaining element rotatable with said shaft within said housing and having a lip extending into the path of said roller when said roller pivots with said swinging door toward the open position of the latter for engaging and retaining said roller when said door is open, and lever means attached to said shaft exteriorly of said housing for rotating said retaining element into a position wherein said lip is away from the path of said roller.

2. In combination with a checking floor hinge for single acting swinging doors having a housing, a spindle projecting from said housing, and an arm attached to said spindle exteriorly of said housing, said arm being adapted to be connected with a swinging door; a hold
